UNITED STATES PATENT OFFICE.

CHARLES E. BUELL, OF NEW HAVEN, CONNECTICUT, ASSIGNOR, BY MESNE ASSIGNMENTS, TO THE UNITED STATES TELEPHONE MANUFACTURING COMPANY, OF NEW YORK, N. Y.

INDIVIDUAL SIGNALING APPARATUS FOR TELEPHONE SYSTEMS.

SPECIFICATION forming part of Letters Patent No. 258,626, dated May 30, 1882.

Application filed July 6, 1881. (No model.)

To all whom it may concern:

Be it known that I, CHAS. E. BUELL, a citizen of the United States, residing at New Haven, in the county of New Haven and State 5 of Connecticut, have invented certain new and useful Improvements in Individual Signaling Apparatus, of which the following is a specification.

My invention relates to that class of individual signaling apparatus in which step-by-step mechanism is set in position by currents of one kind or strength, so as to allow a signal to be given, and the bell is sounded or the signal given by means of a current of another 15 kind or strength.

The object of my invention is to simplify the devices heretofore used for this purpose, and to dispense with the employment of shunting or circuit-closing devices with the step-by-step mechanism for putting the apparatus in operative electrical condition.

My invention consists in making the bell-hammer and the bell movable with relation to one another by means of the step-by-step mechanism, and in so arranging them that the bell will be in position to be struck by the hammer only in a particular condition of the step-by-step mechanism.

In carrying out my invention I make either 30 the bell-hammer and its armature or the bell stationary, and I mount the bell or the hammer upon the step-by-step mechanism, so that a movement will be imparted to it as the step-by-step devices revolve, and it will be carried 35 into and out of position when the bell-hammer will strike the bell if operated.

In the accompanying drawings, Figure 1 represents a telephone or telegraph line having three stations provided with my devices, and 40 shows also the central-office apparatus. Fig. 2 is a side view of the bell-ringing apparatus, showing the bell-hammer mounted upon the escapement-wheel of the step-by-step devices. Fig. 3 is a top view of the escapement and 45 polarized electro-magnetic receiver. Fig. 4 shows the bell carried by the escapement-wheel and the bell-hammer and armature stationary.

Referring to Fig. 2, A represents a polarized 50 electro-magnetic receiver of any preferred

form, provided with a polarized armature, B, to which are attached the pallets of a step-by-step escapement-wheel, C. This escapement-wheel and its pallets may be of any desired form, and may be impelled by clock-work; or 55 the movements of the armature itself may be used for that purpose. Fig. 3 shows a top view of a star-escapement that may be used in the latter way.

Upon the escapement-wheel C is mounted 60 in any suitable manner the bell-hammer lever D, provided with a retractile spring and a neutral armature, as shown, the latter adapted to be attracted by the magnet A and drawn down, so that the hammer will strike the bell 65 E, which is stationary. The lever plays between suitable stops, also mounted upon the wheel C. When the wheel is rotated by the polarized armature-lever B the bell-hammer describes a circle, at one portion only of which 70 can it be made to strike the bell. At that portion it may be made to strike by the action of a current of either polarity, but of greater strength than that used in rotating the wheel.

The operation of the devices upon a line will be understood from Fig. 1. At the various stations upon the line the bell-hammers occupy different positions with relation to the bell, so that no two of them can simultaneously be in 80 position where the bell may be struck. When any particular station is to be called or signaled the escapement-wheels and their attached bell-hammers are simultaneously revolved by the action of reversed electrical impulses upon the electro-magnets A until the bell-hammer at the desired station is brought into 85 position over its bell. A current of sufficient strength to cause the electro-magnet to draw down the armature-lever D and strike the bell 90 is then thrown to line. At other stations the bell-hammers will not be in position to be attracted, or, if attracted, will be so situated that they cannot strike their bells.

In Fig. 4 the armature-lever D is stationary 95 and the bell E is mounted upon the escapement-wheel and is moved into and out of position to be struck by the hammer. The operation of these devices upon a line is substantially the same as in Fig. 1.

Each station upon the line is shown as provided with a circuit-breaking key and with a spring gravity-switch for short-circuiting a telephone and for throwing it into circuit.

- 5 At the central office the devices for producing the desired changes in the polarity and tension of the current consist of a toothed wheel, N, which is turned by a crank-handle, and which vibrates a lever, G, so as to make 10 and break the short circuit of a battery, x, and of a key, k², which increases the tension of the current by short-circuiting the resistance R³. Batteries x and y are placed with the same pole opposed to one another, and x is of approximately 15 twice the number of cells of y. When y is short-circuited x sends, for instance, a positive current to line. When the short circuit of y is broken by the dropping of lever G battery x overcomes battery y and sends a current 20 to line of the opposite polarity and of the same strength.

At the top of each line-strip 4 of the switch-board is a switch-lever, h, connected to line, and capable of being turned to connect the line 25 either to one of a series of buttons, which are shown as connected through a wire, 10, to main line or charging-battery M B and to earth, or to one of a similar series of buttons connected to a wire which leads to a key, K³, and to the 30 signaling apparatus through a switch, S⁶, or directly through said switch to the same apparatus.

At the bottom of each line-strip is a switch-lever adapted to connect said strip to a series 35 of buttons connected through wire 12 to the telephone apparatus M, whose other terminal is connected with switch g, through which a connection may be made with ground or with the terminal button of a series, with any one 40 of which the lower series of switches may be thrown into contact. By these means any line may be connected directly with the telephone apparatus at the central station and to earth, or any two lines may be connected together 45 through said apparatus. Similar telephone apparatus, M', may be interposed between any two lines by means of the two upper longitudinal series of connecting buttons and wires, 88.

The terminals 99 are trunk-line connections, 50 to which any subscriber's line may be connected by throwing the appropriate switch of the longitudinal series to which 9 is connected. M and M' are provided with the usual gravity-switches and local batteries, as shown.

55 The horizontal series of buttons 9 may be used for connecting two lines directly with one another without passing through the telephone apparatus.

Signals are given to the central office in the 60 usual way, either by a circuit-breaking key, which breaks the circuit of the main battery M B, to which every line should be normally connected by its appropriate switch-lever, or by increasing the resistance in the line, or by 65 diminishing it. In the present case the keys at the subscribers' stations transmit a signal by breaking the circuit. Normally the bell-

hammers at the various stations are in different positions with relation to the bells. By operating the pole-changing device N the attendant transmits a series of reversed impulses, which rotate the escapement-wheels at the various stations. When the bell-hammer at the station to be called has been thus rotated to position it is made to strike the bell by the 75 current of increased strength transmitted by operating-key K² and cutting-out resistance R³.

It is obviously within the scope of my invention to operate the neutral armature by a second electro-magnet instead of from the poles 80 of the polarized electro-magnet.

I may also produce the required movements of the escapement mechanism and the bell-hammer by currents differing in other respects than in polarity and tension, and it would be 85 obviously within the scope of the invention to operate the escapement by make and break of a weaker current than that used for ringing the bell. Other changes in the character of the currents will readily suggest themselves to 90 those skilled in the art.

I do not claim in this application the devices shown at the central office, as they form the subject of another application filed by me April 4, 1881, No. 29,884. Other polarity and 95 tension changers may obviously be employed instead of those here shown.

What I claim as my invention is—

1. The combination, substantially as described, of a bell-hammer and a bell, movable 100 with relation to one another into and out of position where the bell-hammer, when operated, will strike the bell, mechanism controlled by an electro-magnet adjusted to be operated by currents of one kind or strength for producing 105 the desired relative movement, and devices adapted to be operated by an electro-magnet and currents of another kind or strength for causing the bell-hammer to strike the bell.

2. The combination, substantially as described, of a bell-hammer and a bell, movable 110 with relation to one another into and out of position where the bell may be struck, devices controlled by a polarized electro-magnet adapted to be operated by reversals of current for 115 producing the desired relative movement, and a neutral armature carried by or attached to the bell-hammer for causing the hammer to strike the bell, and adapted to be operated by a current of either polarity, but differing in 120 strength from the reversed currents.

3. The combination, substantially as described, of step-by-step mechanism controlled by a polarized electro-magnetic receiving-instrument, a bell-hammer lever operated by 125 said step-by-step mechanism and carried into and out of position where it may strike a bell, an armature attached to or carried by the bell-hammer, and a retractor for said bell-hammer lever and armature, adjusted above the 130 tension of the currents used for controlling the step-by-step mechanism.

4. The combination, substantially as described, of an electro-magnet provided with

a polarized and a neutral armature, step-by-step mechanism controlled by the polarized armature, and carrying a bell-hammer lever to which is attached the neutral armature, 5 and a stationary bell arranged to be struck by the hammer when the latter is operated at the proper point in its movement with relation thereto.

5. The combination, upon the same main 10 line, of a series of polarized electro-magnetic receiving-instruments, each provided with a supplemental neutral armature-lever carrying

a bell-hammer, a stationary bell arranged to be struck by the hammer when it is in position for that purpose, and step-by-step mechanisms controlled by reversals of current and carrying the bell-hammer, but arranged to place the bell-hammer at the various stations into position where they may strike the bell at a time different for the various mechanisms. 15

CHARLES E. BUELL.
